UNITED STATES PATENT OFFICE.

CHARLES CRISP, OF LONDON, ENGLAND.

TYPE-CASTING AND SIMILAR MACHINE.

1,072,917.

Specification of Letters Patent.

Patented Sept. 9, 1913.

Application filed March 18, 1911. Serial No. 615,204.

To all whom it may concern:

Be it known that I, CHARLES CRISP, a subject of the King of Great Britain, residing at 17 Throgmorton avenue, in the city and county of London, England, have invented certain new and useful Improvements in Type-Casting and Similar Machines, of which the following is a specification.

This invention relates to type casting operations and embodies the general principles of the machine described in the specification of my Letters Patent, No. 1,006,965.

According to the present invention a series of matrix bearing devices are adapted to be set for casting a line of type. The matrix bearing devices, such as wheels, disks, or the like, are arranged side by side and adapted to be successively actuated or moved angularly in either direction so as to bring the desired matrices into alinement with each other and thus form a complete line, ready for having the metal introduced therein through a molding box of any appropriate construction adapted to form the type, after which the series of matrix bearing devices is returned to its initial or zero position, ready for a new line of matrices to be set for casting.

In order that the said invention may be clearly understood and readily carried into effect I will proceed to describe the same with reference to the accompanying drawings in which:—

Figure 1 is a side elevation of the machine. Fig. 1^a is a plan view of the machine with the mold box removed. Fig. 2 illustrates a side view of the traveling carriage and Figs. 3 to 6 inclusive are detail views thereof. Fig. 7 is a front view of the kicking member and mechanism pertaining thereto, Fig. 8 is a side view thereof and Fig. 9 a side view of the escapement which controls the rotary movement of the kicking member. Fig. 10 is partial view of the kicking member and one of the matrix bearing devices. Figs. 11, 12 and 13 are respectively a plan, sectional elevation and front elevation of an adjustable stop for the traveling carriage. Fig. 14 is an enlarged view of a matrix bearing member and the retaining comb in the operative and inoperative positions. Fig. 15 is a view of the mechanism employed for resetting the stops. Fig. 16 is a partial view of the machine showing the connections of the spring drum serving to return the traveling carriage to its normal po-

sition. Fig. 17 is a view taken at right angles to Fig. 16. Fig. 18 is a view of one of the matrix bearing devices, and Fig. 19 is a sectional view thereof taken on the line 19—19. Fig. 20 is a view showing a plurality of matrix bearing devices with a row of matrices set in alinement. Fig. 21 is a perspective view of a number of matrix bearing devices and the mold box therefor. Fig. 22 is a partial view of one of the matrix bearing devices and the collecting frame pertaining thereto. Fig. 23 is a detail view of the mechanism for operating the escapement pertaining to the kicking member.

The apparatus comprises a suitable frame α provided with fixed horizontal shafts α' carrying a series of matrix bearing disks or rings α^2 . Three shafts α' may be provided each carrying a series of loose pulleys α^3 on which the said matrix bearing rings may ride, the pulleys being mounted on spacing sleeves α^0 (Figs. 18 and 19) which serve to retain the matrix rings the proper distance apart. The periphery of each disk or ring bears matrices (Fig. 20) which may consist of appropriate characters, such as the letters of the alphabet, in capitals, italics, or otherwise, together with such numerals, punctuation and other significant marks as may be desired.

The various matrix bearing disks or rings α^2 are given an angular displacement about the shafts in succession, by mechanism hereinafter described, the extent of the angular movement depending upon the particular matrix that is to be brought into the casting line and the movement of the particular key lever α^4 corresponding with the character of such matrix.

The degree of rotation, and consequently the particular matrix, is determined by means of stops α^5 , arranged to operate in a quadrant like member α^6 situated preferably beneath and concentric with the row of matrix bearing members α^2 and which are maintained in their elevated position and reset in a similar manner to the stops employed in the apparatus described in the aforesaid prior specification. A row of stops α^5 is arranged under each matrix bearing ring α^2 and the number of stops corresponds with the number of matrices carried by the ring.

The matrix bearing disks are normally prevented from rotating by a depression α^7 (Fig. 21) formed in the inner side of each

ring which is adapted to engage with one of the loose pulleys a^8 and retain the ring in its normal position.

Mounted with a capability of intermittent transverse motion is a traveling lug or carriage a^8 , Fig. 2, of the general character described in the aforesaid prior specification containing a series of pins a^9 having a vertical displacement, which carriage travels under each matrix bearing disk a^2 in turn. The pins a^9 correspond in number to the row of stops a^5 under each matrix bearing ring and are actuated directly from the type keys a^4 by universal bars b . On operating a key lever a^4 one of the pins a^9 is driven up and comes in contact with and forces up one of the stops a^5 in the quadrant shaped member a^6 under the matrix bearing disks a^2 , the arrangement enabling the stop 10 to retain the said position. One of the said stops having been thus brought into position motion is imparted to the matrix bearing wheel by means of a kicking member b' slidably mounted upon a square shaft b^2 (Fig. 7) and connected to the traveling carriage a^8 by means of a fork b^3 ; each matrix bearing member is provided with a weight a^{10} which serves to assist the kicking member b' in displacing or imparting motion to 15 said member. Each matrix bearing member is also provided with a number of projections a^3 and the kicking member b' is adapted to strike said projections and impart the desired movement to the matrix bearing members in turn. The matrix bearing member rotating on its shaft is arrested by the projecting stop a^5 . The traveling carriage a^8 is connected with a spring drum b^4 , Fig. 4, or the like which is adapted to 20 impart movement thereto and to an Archimedian screw b^5 . The spring drum b^4 is secured to the carriage by the arm b^9 which tends to draw the same across the machine. The screw b^5 is operatively connected by 25 gearing b^6 , b^7 with the square shaft b^2 which carries the kicking member b' and actuates the same when an escapement b^8 pertaining thereto is operated by the depression of the key lever.

30 The escapement b^8 controls the movement of the traveling carriage and comprises a toothed wheel c , Fig. 9, mounted on the Archimedian screw b^5 and with which a double pawl c' is adapted to engage, movement being imparted to the pawl by the universal bars b actuated by the key levers a^4 .

35 Referring to Figs. 7 and 23, a shaft h extends across the machine in a manner similar to the universal bars b and is connected to each of the latter by rods h' and links h^2 , so that each time a universal bar is operated, the shaft h will be turned. The shaft h carries a bracket h^3 which is provided with an arm h^4 , which is connected by a link h^5 40 with the escapement device b^8 . Conse-

quently, when the shaft h is displaced, a lateral movement is imparted to the escapement device b^8 and the double pawl c' , c'' . The escapement device is returned to its normal position by the spring h^6 .

45 The pawl comprises two members or teeth one of which c' is capable of relative movement to the other c'' and which normally tends to separate from this latter member. When the pawl is moved laterally as above 50 described the screw b^6 is allowed to move a distance equal to the distance between the members of the pawl. This step by step movement is imparted to the carriage a^8 by the spring drum b^4 . In order to return the 55 carriage when it has reached the end of its travel, another spring drum c^2 (Figs. 5 and 6) may be employed which is adapted to be placed under tension when the lever c^{15} hereinafter described for effecting the alinement of the matrices is depressed. The 60 ends of the spring c^3 of the drum are connected to the respective members c^4 , c^5 thereof. The lever c^6 (Figs. 16 and 17) is connected to the rod d^4 pivoted to the alinement lever c^{15} and the link c^7 to the arm b^9 of the spring drum b^4 imparting the step by 65 step movement to the traveling carriage a^8 . As the lines of type are not always of the same length, it is necessary to provide means 70 for stopping the carriage at an intermediate position and prevent it being moved back to the end of the machine by the actuating mechanism. To permit of the carriage being returned and retained in an intermediate position, provision is made for free movement between the parts c^4 , c^5 , of the said spring drum. With this arrangement an adjustable stop c^8 (Figs. 11 to 13) 75 would be set in the desired position in the path of the traveling carriage so as to insure the desired result. The alinement lever c^{15} is pivoted to the framing of the machine at c^{12} and its extremity is connected to the vertical rods d^4 actuating the alining device 80 the operation of which will be hereinafter described. Motion is imparted to the alinement lever by the cam c^{13} which is operatively connected by the belt or chain gearing c^{14} with any suitable type of motor. 85 When the alinement lever c^{15} and the rod d^4 are depressed, the lever c^6 connected to the rod d^4 imparts motion to the returning drum c^2 and through the link c^7 to the traveling 90 carriage.

95 When the carriage meets the stop c^8 the arrangement of the spring drum will allow of the further depression of the lever c^6 even though the carriage is in contact with the aforesaid stop as the two parts c^4 , c^5 95 of the drum are capable of relative movement. When a key lever a^4 is released after being depressed the pins a^9 on the traveling carriage being loose return to their lowest position and the traveling carriage moves to 100

the right coming to rest under the next set of stops the rotation of the screw b^6 permitting the spring drum b^4 to impart the desired movement to the carriage. The stop 5 c^8 is provided with a spring controlled member, or pawl c^{10} which is adapted to engage with a rack c^{11} arranged on the frame of the machine and retain the stop in any position in which it is set.

10 Each of the stops a^5 is capable of selecting two or more matrices in a manner similar to that described in connection with the matrix bearing wheels in the aforesaid prior specification. The matrix bearing disks a^2 are 15 capable of rotation in either direction, and are so balanced that if slightly displaced from the normal position the weights a^{10} thereon will tend to rotate in the direction of displacement. In order to reverse the 20 direction of movement of the matrix disks a change key is provided which is arranged to control two clutches d, d' , Fig. 7, adapted to couple up the square shaft b^2 carrying the kicking member b' with one or other 25 of the two sets of gearing b^6, b^7 transmitting movement from the Archimedean screw b^5 .

The shaft b^2 carries at each end thereof a pinion mounted loose upon said shaft, each 30 of which is adapted to be rotated integrally therewith by the clutch members d and d' . Assuming the clutch d to be engaged with its adjacent pinion and the clutch d' disengaged, motion will be transmitted from 35 the shaft b^5 through the gear b^6 carried directly thereby to the pinion mounted on the squared shaft b^2 . When the clutch d is engaged, it will, therefore, be seen that the shaft b^2 will be rotated in an opposite direction from the shaft b^5 , since motion is 40 transmitted from the shaft b^5 to the shaft b^2 directly by two intermeshing gears. The pinion adjacent the clutch d' , however, does not mesh directly with a gear carried by 45 the shaft b^5 , as in the former case, but a counter-shaft is employed adjacent the shaft b^5 , said counter-shaft being mounted in the bracket b^9 . This counter-shaft carries a small pinion b^8 and the gear 50 b^7 . The pinion b^8 meshes with a corresponding pinion on the screw shaft b^5 and the gear b^7 meshes directly with the pinion carried by the squared shaft b^2 . When the clutch d' is engaged, it will, therefore, be seen that the pinion carried by screw 55 shaft b^5 rotates the pinion b^8 in an opposite direction to the screw shaft, and hence, the gear b^7 rotates in an opposite direction to the screw shaft b^5 . Consequently, the 60 pinion on the squared shaft b^2 rotates in an opposite direction to the gear b^7 or in the same direction as the screw shaft b^5 . The shifting of the clutches, therefore, causes a reversal in the direction of rotation of the 65 squared shaft b^2 .

Motion is imparted to the clutches by the links d^{3x}, d^{4x} connected to the change key or keys.

Instead of using a number of stops a^5 for each matrix bearing disk one stop may 70 be provided which is capable of being pushed up to varying heights. With such arrangement it is possible to select a number of matrices on a disk which is capable of rotating in one direction only, the disk 75 in this case being provided with projections d^3 equal in number to the varying heights to which the stop can be pushed up.

When a complete line of matrices has been 80 brought into position, the final alinement is effected by the alinement lever c^{15} being depressed by the cam c^{13} so as to impart a corresponding movement to the two rods d^4 (Fig. 1); one of said rods serving to bring a knife d^5 into engagement with 85 notches d^6 formed in the inner edges of the matrix bearing rings a^2 . The knife d^5 is mounted in the frame so as to extend across the whole series of matrix bearing rings and is depressed against the action of springs d^7 90 by means of cams d^8 mounted on another shaft d^9 adjacent thereto. This latter shaft is actuated by means of suitable projections e, e' carried by the respective rods d^4 pertaining to the alinement lever, one projection e serving to actuate the same on the downward movement and the other projection e' on the upward movement of the lever. The notches d^6 are thereby alined 95 or registered by the continuous knife d^5 , 100 and hence the matrices are brought into exact alinement.

When a line of matrices has been set and the type cast, the matrix bearing rings a^2 have to be returned to their initial position 105 ready for the next setting and for this purpose a collecting frame e^2 (Figs. 1 and 22) is caused to rotate upon a shaft e^3 and engage with projections e^4 on the inner edges of the rings. The collecting frame e^2 comprises a pair of spring controlled levers e^5 110 between which a knife shaped member e^6 is arranged, said member being normally in close proximity to the projections e^4 on the matrix bearing rings. This knife shaped member e^6 is pivotally attached to the said levers and extends inside the whole series of 115 matrix rings. When the rods d^4 associated with the alinement lever are depressed a pawl e^7 (Fig. 1) operatively connected therewith is adapted to impart movement to one of the levers e^5 by engaging with a projection e^{10} thereon and thereby bringing the knife shaped member e^6 into the position shown in broken lines in Fig. 22 ready for 120 engaging with the projections e^4 inside the matrix rings a^2 . The extremity of one of the levers e^5 is at the same time brought into engagement with the bell crank lever 125 or pawl e^8 pivoted to the frame of the ma- 130

chine. The knife shaped member e^6 is thus retained in position for engaging with the projections e^4 on the matrix rings a^2 when it is released and actuated by the spring f . A trip e^9 is also provided on one of the vertical rods d^4 connected to the alinement lever and this latter is adapted to release the pawl e^8 engaging with the lever e^5 . The release is effected on the upward movement of the rods d^4 and owing to the springs f secured to the knife shaped member e^6 and the lever e^5 of the collecting frame e^2 a rapid rotary movement is imparted to the member e^6 ; the member e^6 will thus engage with the projections e^4 of the matrix rings a^2 and kick or return the same to their initial position. In order to insure the sudden disengagement of the knife shaped member from the matrix rings when the rings have reached their normal position suitable leaf springs f' may be provided which are adapted to move the said member angularly when the collecting frame is actuated as aforesaid.

A comb-like device f^2 , Fig. 14, having flexible blades f^3 , f^4 is placed so as to receive the projections d^3 on the matrix rings when they are being returned to their initial position and thereby retard the motion of said rings so that the depression a^7 (Fig. 21) formed in the inner side of each ring may engage with the upper one of the loose pulleys a^3 . After the comb-like device has retarded the motion of the rings a^2 , it is moved out of engagement with the projections d^3 thereon and the rings are retained in the normal position by the aforesaid depression a^7 . The device comprises two members f^x , f^{2x} to which the respective blades f^3 , f^4 are connected, the member f^x being connected to the member f^{2x} of the comb-like device so as to be capable of movement thereon, this connection being effected by suitable links f^{11} or the like; the relative positions of the members are maintained by an intermediate spring f^{3x} . This spring f^{3x} normally retains the two members f^x and f^{2x} in the relative position shown in broken lines in Fig. 14, so that the blades assume a position substantially parallel with each other. The comb-like device f^2 is held in this position away from the projections on the matrix rings a^2 by a spring f^5 , but when the rod d^4 is depressed, a trip f^0 thereon engages with the member f^1 of the comb and turns the same into the full line position, said comb being retained in this position by the projection f^0 thereon engaging with the pawl t carried by the frame a of the machine. Consequently, when the matrix rings are being returned to their normal position after setting, the projections d^3 thereon will strike the blade f^3 and will cause the member f^x to be turned into the position shown in full lines in Fig. 14 so that the blades

f^3 , f^4 will be inclined toward each other and will serve to retain the projection d^3 between them. The member f^x of the comb-like device is retained in the last mentioned position by the extremity t' thereof engaging with a pawl t^2 pivoted to the member f^{2x} of the device. When the rod d^4 rises the trip f^{10} thereon releases the pawl t and allows the spring f^5 to return the comb device to its normal position out of engagement with the matrix rings; the spring f^{3x} at the same time serves to move the member f^x to its inoperative position, as the movement of the comb-like device disengages the extremity t' of the member f^x with the pawl t^2 , for, during said movement, the pawl is retained by the arm t^3 thereof engaging with the projection t^4 on the frame of the machine.

Means may be provided whereby the retaining stops before mentioned will when requisite be brought to their initial position by a bar or other suitable mechanism engaging therewith.

The aforementioned stops a^5 are brought to their lowest position by the downward movement of the alinement lever c^{15} which depresses a frame a^{10} (Fig. 15) engaging with an enlargement a^{11} formed at the bottom of each stop. The frame a^{10} carries a rod a^{12} which is free to move in the socket or guide a^{13} , and motion is imparted to the frame by the forked member a^{14} pivotally mounted on one of the rods d^4 . On the downward movement of the rods d^4 the arm a^{15} of the forked member a^{14} and the frame a^{10} move together until the arm a^{15} passes a projection a^{16} mounted on the frame of the machine. When the arm a^{15} passes the projection a^{16} it swings outward and the downward movement of the frame a^{10} ceases. The release of the member a^{14} allows the rods d^4 to further descend and the necessary length of stroke to be given to the other movements which require it. During the upward movement of the rods d^4 the spring a^{17} pulls the arm a^{15} into the perpendicular position thus preventing it from fouling the projection a^{16} .

The matrix rings and corresponding mechanism are carried by the frame a which is capable of movement along the bed b^{11} of the machine. The frame a of the apparatus is capable of movement along a bed b^{11} and is operatively connected, through the links b^{13} , b^{14} , with a cam b^{12} . When the type is to be cast the frame is drawn along the bed b^{11} so as to bring the matrix rings up to the molding box b^{15} ready for the introduction of the metal from the pot b^{16} .

What I claim and desire to secure by Letters Patent of the United States is:—

1. A line casting machine comprising in combination, a plurality of wheels, matrices on the peripheries of said wheels, a kicking

- a rotating movement to said wheels when the said keys are operated, a change key for reversing the direction of rotation of said wheels by the kicking member, a quadrant device arranged in proximity to the peripheries of said wheels, retaining stops carried by said quadrant device, a traveling carriage, pins carried by said carriage, means for elevating said pins and retaining stops, 5 a grid device for resetting the retaining stops, a mold box, means for bringing the matrices up to said mold box for casting, a collecting frame adapted to engage with the projections on the inner edges of said 10 wheels and rotate the same to their normal position after the casting operation has been effected, and a comb-like device adapted to bring the wheels to rest in the normal position. 15 20 10. A line casting machine comprising in combination, a plurality of wheels, matrices on said wheels, projections on the inner edges of said wheels, a plurality of keys, a kicking member for successively imparting a rotating movement to said wheels, when 25 said keys are operated, a double pawl escapement, a change key for reversing the direction of rotation of said wheels, a quadrant device arranged in proximity to the peripheries of said wheels, retaining stops 30 carried by said quadrant device, a traveling carriage, means for actuating said carriage, pins carried by said carriage, means for elevating said pins and retaining stops, a grid device for resetting the retaining stops, a 35 device for alining the matrices, a mold box, means for bringing the matrices up to said mold box for casting, a collecting frame adapted to engage with the projections on the inner edges of said wheels and rotate 40 the same to their normal position after the casting operation has been effected, and a comb-like device adapted to bring the wheels to rest in the normal position. 45

In testimony whereof I affix my signature 45
in presence of two witnesses.

CHARLES CRISP.
